UNITED STATES PATENT OFFICE.

MONROE DAVIS, OF ENID, OKLAHOMA, ASSIGNOR OF ONE-TWELFTH TO GEORGE D. WILSON, OF ENID, OKLAHOMA.

THRESHING-MACHINE.

1,226,865.

Specification of Letters Patent. Patented May 22, 1917.

Application filed October 2, 1916. Serial No. 123,412.

To all whom it may concern:

Be it known that I, MONROE DAVIS, a citizen of the United States, residing at Enid, in the county of Garfield and State of Oklahoma, have invented certain new and useful Improvements in Threshing-Machines; and I do declare the following to be a full, clear, and exact description of the invention, such as will enable others skilled in the art 10 to which it appertains to make and use the same.

My invention relates to improvements in threshing machines of the general type shown by my U. S. Patent 1174398 of March 15 7, 1916, the object being to provide a machine which will be simple and comparatively inexpensive yet even more efficient than that shown by the patent referred to.

With the foregoing general object in view, 20 the invention resides in certain novel features of construction and unique combinations of parts to be hereinafter fully described and claimed, the descriptive matter being supplemented by the accompanying 25 drawings which constitute a part of this application and in which:

Figure 1 is a side elevation of the improved machine;

Fig. 2 is substantially a central vertical 30 longitudinal section thereof;

Figs. 3, 4 and 5 are vertical transverse sections taken on the planes of the lines 3—3, 4—4 and 5—5 of Fig. 2;

Fig. 6 is a perspective view of parts of 35 the main rotary beater;

Fig. 7 is a transverse section thereof;

Fig. 8 is a detail longitudinal section of 40 a portion of the auxiliary beater;

Fig. 9 is a transverse section thereof.

In specifically describing the construction shown in the drawings above briefly described, similar characters will be employed to designate corresponding parts throughout the several views and reference will be 45 herein made to the numerous elements by their respective indices. To this end, the numeral 1 designates a frame mounted on front and rear wheels 2 and 3 respectively and provided with a tongue 4 by means of 50 which it may be drawn from place to place.

Mounted on the frame 1 is a threshing chamber 5 which decreases in diameter from one end to the other, said chamber consisting of a plurality of axially aligned frusto-cone shaped sections 6 with their larger ends

all disposed in the same direction, contracted at 7 and joined to the smaller ends of adjacent sections, said contracted portions 7 constituting circumferentially extending internal shoulders which face the smaller end 60 of the chamber 5.

The larger end of the chamber 5 is closed by an end plate 8 having at its lower edge an opening from which a frusto-cone shaped inlet hood 9 extends outwardly, the larger 65 outer end of said hood having an aperture 10 into which one end of a feed pipe 11 projects, said pipe serving to conduct the unthreshed grain into the chamber 5 when suction is created through said chamber and 70 pipe by means to be described.

A fan casing 12 is provided at the smaller end of the chamber 5 and a single horizontal shaft 13 extends longitudinally through the center of said chamber and casing, said shaft 75 being provided with a pulley 14 by means of which it may be driven and preferably having a fly-wheel 15 for steadyng its motion. A suction fan 16 is mounted on shaft 13 within the casing 12 for creating a strong 80 suction or current of air through the pipe 11 and chamber 5, said current being expelled through the outlet 17 of the casing 12. The portion of the shaft 13 in the chamber 5 carries a plurality of hubs 18 having 85 laterally extending ears 19 to which a plurality of radially disposed beater arms 20 are bolted or otherwise secured, said arms being spirally arranged as seen most clearly by reference to Fig. 6 and being so twisted 90 as to cause them to assist in moving the unthreshed grain and straw through the chamber 5 toward the smaller or outlet end of the latter. The outer ends of the arms 20 are directed angularly toward said outlet 95 end as shown clearly in Fig. 2, whereby as the material within the chamber 5 is drawn into contact with said arms by the current of air passing through the chamber, said arms will deflect the same outwardly as well 100 as throwing it by centrifugal force. This operation is sufficient to separate the grain from the straw by centrifugal power, the threshed grain being discharged from chamber 5 through a plurality of outlet tubes or the like 21 which depend from the sections 6 immediately in advance of the shoulders 7, said tubes discharging into a horizontal grain conduit 22 which extends beneath the chamber 5 and casing 12.

One end of conduit 22 delivers into a pit 23 at the lower end of a grain elevating conduit 24, and for feeding the grain from said conduit 22 into the pit 23, a combined conveyer and auxiliary beater 25 is provided. The device 25 consists of a horizontal tubular shaft 26 which extends through the conduit 22 and is formed at intervals with spirally arranged slots 27, flat metal bars 28 being passed through said slots and having their ends twisted in opposite directions to provide conveyer arms 29 disposed at angles to the planes in which they travel (see more particularly Figs. 2, 8 and 9). The shaft 26 is rapidly rotated from shaft 13 by means of a belt 30 and pulleys 31 and the arms 29 thereof thus serve to perform an auxiliary threshing action on the grain in the conduit 22. This is a rather important feature of the machine since if any heads of grain have passed into said conduit, the grain will be beaten therefrom by the combined beater and conveyer 25, the completely threshed grain being fed into the pit 23 while this operation is taking place.

An endless belt elevator 32 is mounted in the vertical conduit 24 for carrying the grain from the pit 23 and discharging it through the laterally and downwardly directed upper end 33 of said conduit. The grain may be received in sacks but will preferably be deposited into a wagon body. For removing any chaff and other dust from the threshed grain, a pipe 34 leads from the discharge end 33 of conduit 24 into the larger end of the chamber 5 whereby suction will be created through said pipe to draw such chaff and dust and redeposit the same into the aforesaid chamber from which it is adapted to be expelled with the straw, the latter being drawn into and expelled from the casing 12 by the fan 16. Any suitable valve 35 will preferably be provided for controlling the strength of the air current passing through pipe 34.

In operation, the shaft 13 will be rotated by applying power to the pulley 14, the fan 16, the beater arms 20, device 25, and conveyer 32 being all driven at the same time and at a comparatively high rate of speed. The fan 16 and the angularly disposed arms 20 cooperate in producing a strong suction or current of air through the pipe 11 and chamber 5, and in discharging this current through the outlet 17 of casing 12. This current of air as it passes through the inlet to the fan travels in a straight line and the column of moving air is of a diameter corresponding at its ends with the diameter of the inlet and the eye of the fan, thus leaving substantially a calm or body of dead air surrounding the column of moving air except when the small current of air through the pipe 34 enters the threshing chamber.

When the unthreshed grain enters the chamber through the feed pipe 11, it is in a mass and this mass is rapidly rotated by the arms 20 whereupon the grain is threshed by centrifugal force. This force causes the grain to rotate around the inner side of the wall of the threshing chamber, coming wholly within the dead air zone, while the straw being lighter goes out through the fan in the moving air, being held within this column of air by the arms 20. This causes the separation of the threshed wheat or other grain from the straw and such separation is facilitated materially by the cone-shape of the numerous sections of the threshing chamber, it being apparent that when the threshed grain is thrown around in contact with these cone-shaped sections, it travels toward the larger ends thereof. This gives a method of separation wherein the straw is passed forwardly in the threshing chamber, while the threshed grain is traveling rearwardly by reason of the shape of said chamber. The present machine is so constructed that the column of moving air sweeps directly over the shoulders at the bottom of the threshing chamber but not so close elsewhere. This permits the threshed grain to drop into the recesses formed by the shoulders while the straw and chaff is swept onward by the moving air column 4.

In conduit 22, the combined conveyer and beater 25 performs an auxiliary threshing operation and thus insures that if any grain has entered the conduit 22 without being separated from the heads, this separating will here take place. While this operation is going on, the unthreshed grain is being fed into the pit 23 by the arms 29 and from said pit it will be conducted by the elevator 32 to be discharged through the delivery end 33 of the vertical conduit 24. As grain is thus leaving the machine, the air current created through pipe 34 will remove all chaff and dust therefrom and return it to the chamber 5 to be expelled with the straw.

The improved machine constructed substantially as described is highly efficient and is adaptable for use on all kinds of small grain, it being well suited for threshing rice inasmuch as it will not crack the grains nor remove the hulls therefrom.

In the foregoing I have described certain specific details of construction for the attainment of probably the best results, and in the accompanying drawings such details have been shown, but I wish it understood that numerous changes may be made within the scope of the invention as claimed without sacrificing the main advantages thereof.

I claim:

1. A threshing machine comprising a horizontally elongated imperforate threshing chamber having in one end an unthreshed grain inlet and in its other end a

straw and chaff outlet, said chamber having a plurality of longitudinally spaced circumferential shoulders on its interior and being decreased in diameter from each shoulder to the next succeeding shoulder, said chamber having in its lower side a plurality of threshed grain outlets disposed immediately in advance of said shoulders; in combination with means in the chamber for threshing the grain and separating the same from the straw by centrifugal force.

2. A threshing machine comprising a horizontally elongated imperforate threshing chamber consisting of a plurality of axially aligned frusto-cone shaped sections with their larger ends disposed in one direction and contracted to form annular internal shoulders to which the smaller ends of adjacent sections are united, said chamber having at opposite ends an unthreshed grain inlet and a straw and chaff outlet and having in its lower side a plurality of threshed grain outlets disposed immediately in advance of said shoulders; in combination with means in said chamber for threshing the grain and separating the same from the straw by centrifugal force.

3. A threshing machine comprising a horizontally elongated imperforate threshing chamber decreased in diameter from one end to its other and having in its larger end an unthreshed grain inlet while at longitudinally spaced points said chamber is formed with annular shoulders facing its smaller end and immediately in advance of said shoulders with threshed grain outlets, the latter being disposed in the lower side of said chamber, a fan casing into which the contracted end of the aforesaid chamber discharges, a horizontal shaft passing longitudinally through the center of said chamber and through said casing, means on said shaft for threshing the grain and separating the same from the straw by centrifugal force, and a fan mounted on said shaft in the fan casing for drawing the unthreshed grain through the chamber and for discharging the straw and chaff.

4. A threshing machine comprising a horizontally elongated threshing chamber decreased in diameter from one end to its other and having in its larger end an unthreshed grain inlet while at longitudinally spaced points said chamber is formed with annular shoulders facing its smaller end and immediately in advance of said shoulders with threshed grain outlets, the latter being disposed in the lower side of said chamber, a fan casing into which the contracted end of the aforesaid chamber discharges, a horizontal shaft passing longitudinally through the center of said chamber and through said casing, means on said shaft for moving the unthreshed grain circumferentially to separate the grain from the straw by centrifugal

force, a fan mounted on said shaft in the fan casing for drawing the unthreshed grain through the chamber and for discharging the straw and chaff, and a horizontal conveyer conduit into which the threshed grain is deposited from the aforesaid outlets.

5. A threshing machine comprising a threshing chamber and means for creating a strong air current therethrough to carry the unthreshed grain through said chamber and discharge the straw therefrom, means for receiving the threshed grain from the threshing chamber, a conveyer conduit for carrying said grain from said means, and a suction pipe leading from said conduit to the threshing chamber, whereby suction will be created through said pipe to draw all chaff and dust from the threshed grain.

6. A threshing machine comprising an elongated threshing chamber having at one end an unthreshed grain inlet and at its other end a straw and chaff outlet, said chamber having a threshed grain outlet between its ends, threshing means in the aforesaid chamber, a suction fan at the delivery end of said chamber for creating a strong draft of air therethrough and for discharging the straw, a conduit extending horizontally beneath the aforesaid chamber to receive the grain therefrom, an elevator conduit rising from the aforesaid conduit and adapted to carry the grain therefrom, and a suction pipe leading from said elevator conduit to the threshing chamber whereby suction will be created in said pipe to remove all chaff and dust from the threshed grain.

7. A threshing machine comprising a horizontally elongated imperforate threshing chamber consisting of a plurality of axially aligned frusto-cone-shaped sections with their larger ends disposed in one direction and contracted to form annular internal shoulders to which the smaller ends of adjacent sections are united, a closure for the larger end of the threshing chamber having at its lower edge an unthreshed grain inlet, a fan casing with which the smaller end of said chamber communicates, a shaft extending axially through the threshing chamber and said fan casing, a plurality of threshing arms radiating from said shaft for threshing the grain and whirling the straw and grain circumferentially to separate the latter from the former by centrifugal force, said threshing chamber having a series of threshed grain outlets at its lower side disposed at the aforesaid shoulders, and a fan on the shaft located within the aforesaid fan casing for drawing the chaff and straw from the threshing chamber.

8. A threshing machine comprising a horizontally elongated imperforate threshing chamber consisting of a plurality of axially aligned frusto-cone-shaped sections with their

- 4
larger ends disposed in one direction and contracted to form annular internal shoulders to which the smaller ends of adjacent sections are united, a closure for the larger 35
5 end of the threshing chamber having at its lower edge an unthreshed grain inlet, a fan casing with which the smaller end of said chamber communicates, a shaft extending axially through the threshing chamber and
10 said fan casing, a plurality of fan-like threshing blades radiating from the aforesaid shaft and inclined toward the contracted end of the threshing chamber, and a fan secured on said shaft and disposed in the fan 40
15 casing, said blades serving to thresh the grain and the inclination of said blades co-operating with the draft of air caused by the fan to throw the straw and grain outwardly.
20 9. A threshing machine comprising a horizontally elongated imperforate threshing chamber, a fan casing with which one end of said chamber communicates, a fan in said casing for drawing a current of 45
25 air through said chamber, a closure for the other end of said chamber having an inlet of considerably less size than said closure to direct the air current through a restricted portion of the chamber to leave substantially a void around said current, means in said chamber in the path of the 50
30 rear ends of said units. 55

In testimony whereof I have hereunto set my hand in the presence of two subscribing witnesses.

MONROE DAVIS.
